UNITED STATES PATENT OFFICE.

AUSTIN S. LADD, OF LOWELL, MASSACHUSETTS, ASSIGNOR, BY DIRECT AND MESNE ASSIGNMENTS, TO JAMES W. BENNETT, ALBERT M. MOORE, KIRKLEY HYDE, AND FREDERICK TAYLOR, ALL OF SAME PLACE.

WOOD-RIM PULLEY.

SPECIFICATION forming part of Letters Patent No. 284,133, dated August 28, 1883.

Application filed May 7, 1883. (No model.)

To all whom it may concern:

Be it known that I, AUSTIN S. LADD, a citizen of the United States, residing at Lowell, in the county of Middlesex and Commonwealth 5 of Massachusetts, have invented certain new and useful Improvements in Wood-Rim Pulleys, of which the following is a specification.

My invention relates to means of connecting a wooden-rim foundation to a metallic spider 10 directly and without the use of screws or bolts and nuts, or other commonly-used fastenings.

In the accompanying drawings, Figure 1 is a side elevation of my improved pulley, a part 15 to show the ledges at the ends of the arms and the middle felly or rim-foundation; Fig. 2, a central cross-section of the same, taken on the dotted line X-X in Fig. 1.

The spider A consists of the hub B and arms 20 B', preferably cast in one piece with the hub; but the hub and arms may be connected in any usual way. Each arm B', on each edge thereof, at or near its outer end, is provided with one or more ledges, C C', which project 25 toward the arms next adjacent. A central wooden felly, D, of the shape of an arc of a circle, long enough to reach from one arm to the next between said ledges, the ends of the central felly being of such a shape as to fill the 30 spaces between said ledges, is inserted between each pair of said arms and within said ledges to form a rim-foundation, to which lags or outer fellys, D', may be attached by glue and brads,

or screws, or nails, in the ordinary manner, the lags being sawed out to the shape required, and the rim of the pulley thus formed is finally turned true. The shape of the bearing-ends 35 of the arms may be varied without departing from the principle of my invention. The central felly forms a foundation on which to build 40 the wooden rim of the pulley, and should be made to fit so closely between the arms of the spider as to require to be pressed into place. The spider will require no fitting, except boring 45 out the central hole for the shaft on which the pulley is placed, and except forming the key-seat by which the pulley, if to be used as a fast pulley, may be keyed to the shaft. The pulley above described is therefore constructed 50 at slight expense.

I claim as my invention—

1. The combination of a metallic spider and a wooden-rim foundation, said foundation and the outer ends of the arms of said spider being 55 adapted to engage directly with each other and to retain said foundation in place, as and for the purpose specified.

2. The combination of the spider, provided with arms having ledges, and the foundation-pieces or fellys adapted to reach from one arm 60 to the next, and to be held in place by said ledges, as and for the purpose specified.

AUSTIN S. LADD.
